(57) **CLAIM**

The ornamental design for a boom arm for agricultural sprayer, as shown and described.

DESCRIPTION

FIG. 1 is a top plan view of a boom arm for agricultural sprayer;

FIG. 2 is a bottom view thereof;

FIG. 3 is an isometric view thereof; and,

FIG. 4 is an isometric view thereof, showing the design from the opposite side to the shown in FIG. 3.

The claimed boom arm for agricultural sprayer is used for agricultural spraying purposes.
